CARTON SEALING MACHINE

Franklin M. Willbrandt, Battle Creek, Mich., assignor to Battle Creek Bread Wrapping Machine Company, Battle Creek, Mich.

Application September 15, 1947, Serial No. 773,947

4 Claims. (Cl. 93—2)

1

This invention relates to improvements in a carton sealing machine.

The principal objects of this invention are:

First, to provide a semi-automatic sealing machine for rapidly closing and sealing food cartons or the like and the liner bag positioned within the cartons.

Second, to provide a relatively inexpensive sealing machine which will reduce the number of motions and time required for an operator to seal a liner bag and enclose the bag in a sealable, foldable carton.

Third, to provide a work table or support for foldable cartons which will facilitate the erecting of the cartons and heat sealing of the cartons and liner bags positioned therein.

Fourth, to provide a semi-automatic folding and sealing machine which is readily adjustable to accommodate cartons of different sizes.

Fifth, to provide a semi-automatic folding and sealing machine which may be manufactured at low cost.

Other objects and advantages pertaining to the details and economies of the invention will be apparent from the following description and claims.

The drawings, of which there are two sheets, illustrate a preferred form of my sealing machine and one example of the type of carton and liner which it is designed to fold and seal.

Fig. 1 is a plan view of the sealing machine.

Fig. 2 is a fragmentary cross sectional view along the line 2—2 of Fig. 1 and showing the machine in the first step of the sealing operation.

Fig. 3 is an enlarged fragmentary elevational view of the bag crimping jaws illustrated in Fig. 2.

Fig. 4 is a fragmentary cross sectional view along the line 4—4 in Fig. 1.

Fig. 5 is a fragmentary cross sectional view along the line 5—5 in Fig. 1.

Fig. 6 is a fragmentary cross sectional view along the line 6—6 in Fig. 1 and showing a carton ready to be set through the automatic portion of the sealing machine.

Fig. 7 is an enlarged fragmentary cross sectional view similar to Fig. 6 but showing the sealing machine at a second step in the manual sealing operation.

Figs. 8, 9 and 10 are fragmentary perspective views of one form of carton which the machine is arranged to seal in successive steps of the folding operation.

My sealing machine is particularly designed for relatively small food packaging establishments, such as frozen food packers, whose pro-

2

duction does not warrant the installation of expensive automatic packing machinery but whose costs can be greatly reduced by increasing the output of workers packaging the company's product. My machine is designed to form part of the folds and seals in a foldable outer carton and an inner bag or liner to eliminate several motions on the part of the operator performing the manual portions of the packing and sealing operation.

My sealing device consists of a pair of frame members 1 having raised parallel side rails 2 which are connected by a series of five transversely extending top panels 3 screwed or otherwise secured to the tops of the rails. The top panels are spaced to define a series of transverse slots 4 therebetween and the frame members 1 are further connected beneath the top panels by a pair of transversely extending guide rods 5. The frame is arranged to be supported upon a base or work table 6 at a convenient height in front of the operator.

Slidably mounted on the guide rods 5 are a pair of longitudinally extending parallel support bars 7 which extend beneath the slots 4 in the top panels. Secured to each of the support bars 7 is a forward vertical support 8 having laterally outwardly extending arms 9 (see Fig. 5) and a vertical fence portion 10 extending through the forward two slots 4 and above the top panels 3. The fence portions 10 are secured by means of spacer sleeves 11 and bolts 12 to a pair of end fold plates 13 which extend longitudinally of the machine in parallel relationship. Each of the fold plates 13 consists of an upper section 14 and a lower section 15 which define therebetween the rearwardly and upwardly extending curved slot 16 which commences at the surface of the top panels.

The support bars 7 have connected thereto near their rear ends the rear vertical support members 17 which extend laterally outwardly and upwardly through the rear two slots 4 in the top panels. The rear support members 17 are connected by means of the bolts 18 to a pair of sealing plates 19 having obliquely serrated surfaces as shown. Coil springs 20 positioned between the sealing plates and the rear support members and around the bolts 18 yieldingly urge the sealing plates toward each other and in slightly closer spaced relationship than the fold plates 13. Electrical heating elements 21 are secured to the backs of the sealing plates and arranged to be supplied with electric current through conductors 22. Secured to the underside of one of the top

panels 3 and in the middle of the machine is a downwardly extending pin 23 around which is rotatably positioned a collar 24. The upper end of the collar has secured thereto a double armed crank member 25 having equal arms extending generally to the front and rear of the machine. The ends of the arms 25 are pivotally connected to links 26 which extend obliquely outwardly and are pivotally connected to the support bars 7 preferably at the mid-points thereof. The lower end of the sleeve 24 is secured as by welding to a lever 27 which extends beyond the side of the top panels 4 and is bent upwardly as at 28 (see Fig. 4) to a horizontal ear 29. A bracket 30 secured to the side top rail 2 defines an arcuate slot 31 through which the knurled thumb screw 32 extends to engage the ear 29 and releasably clamp it to the bracket.

Movement of the thumb screw 32 along the arcuate slot 31 rotates the sleeve 24 and crank 25 about the pin 23 causing the links 26 to move the support bars 7 laterally toward or away from each other on the guide rods 5. The end folding plates 13 and sealing plates 19 being carried on the support bars are also moved closer together or farther apart to accommodate cartons of varying sizes.

Secured to the front of the frame members 1 are a pair of brackets 33 which support a side sealing plate 34 extending transversely and vertically across the front of the machine. The lower edge of the side sealing plate is notched or toothed as at 35 and arranged to cooperate with a movable jaw member 36 mounted on the ends of arms 37. The arms 37 are fixedly mounted on a shaft 38 extending between the straps 39 secured to the brackets 33. A link 40 connected to the lever 40' on the shaft 38 extends downwardly to a foot pedal 41 permitting the movable jaw 36 to be drawn tightly against the toothed edge of the front sealing plate. The sealing plate is provided with an electrical heating element 42 arranged to be supplied with current through the conductor 43. The toothed lower portion of the sealing plate 34 will be heated along with the surface of the plate.

Secured to the back of the lower edge of the sealing plate 34 is a sealing bar 44 provided with a projecting tongue 45 and a stop plate 46. The tongue 45 is arranged to cooperate with a transversely grooved bar 47 on the back of the movable jaw 36 to heat seal the open end of a liner bag, heat for the process being obtained by conduction from the side sealing plate 34.

The brackets 33 are provided with pivot pins 48 which are secured to the rearwardly extending ears 49 formed on the ends of a transversely extending work support 50 having a forwardly turned flange 51 along the lower edge thereof. Stop pins 52 extend through the brackets 33 and straps 39 to limit the downward movement of the ears 49 and work support about the pivot pins 49 and the top of the work support 50 is preferably proportioned so that it will strike the front edge of the top panel 3 as illustrated in Fig. 7 when it has exposed the front surface of the side sealing plate 34.

The sealing machine is designed to operate on foldable cartons made from blank stampings of cardboard or similar material preferably wax coated so as to be heat sealable. One example of this type of carton is illustrated at 53 in Figs. 8, 9 and 10. For the purposes of description the carton is formed of a scored blank stamping having top and bottom walls 54, side walls 55 and

5 with top end closure flaps 56, bottom end closure flaps 57 and side end closure flaps 58. A side sealing flap 59 is provided along the edge of the top panel 54. The side end sealing flaps 58 are scored diagonally as at 60 and the bottom end sealing flap is provided with a triangular score 61.

The carton just described is arranged to enclose and support a relatively weak bendable liner bag made of cellophane or some similar material which is illustrated in exaggerated cross sectional thickness at 62 in Fig. 7. In operating the machine the operator will take a filled bag 62 and press the open end thereof between the jaws 36 as indicated by the dotted lines in Fig. 2. Operation of the foot pedal 41 will then heat seal and crimp the end of the bag and while this operation is taking place, the operator may place a partially folded blank carton on the work support with one hand as indicated in Fig. 2. The sealed bag may then be placed on the carton blank on the work support and the top and side walls of the carton folded around the bag and the sealing flap 59 brought down over the back of the side wall 60. During this operation the operator will have both hands free to manipulate the folds of the carton and the weight of the carton and the contents will be partially supported on the flange 51 of the work support. When the folding of the carton is complete the operator may lift the carton from the work table and place it underneath the flange 51 raising the work support about its pivots 48 until the upper edge of the plate 50 strikes the front of the top panel 3. The operator may then press the side sealing flap 59 against the side sealing plate 34 as is clearly shown in Fig. 7. The lower edge of the work table will act as a top guide and the operator may press the carton firmly against the sealing plate and slide it transversely of the plate without fear of sliding off the plate or burning his hands on the sealing plate.

After the sides of the carton are sealed the carton is placed on the front of the top panel as illustrated in Fig. 6. The work support will fall back in front of the sealing plate 34 as a shield and the top end closure flaps 56 are manually folded downwardly forming triangular folds in the side end flaps 58 as shown in Fig. 9. The side end closure flaps are then folded inwardly as shown in Fig. 9 forming triangular folds in the bottom end flaps. These folds are conveniently made at each end of the carton at the same time, the operator having both hands free and the weight of the carton being supported on the top panel. The bottom end closure panels now lie on the surface of the front top panel 3 and the partially folded carton may be pressed by the operator between the end folding plates 13 where the curved slot 16 will pick up the end sealing flaps and fold them upwardly as the carton is pushed between the plates. After the end folding plates have folded the bottom flaps 53 against the ends of the carton, the carton may be slid on between the end sealing plates 19 to heat seal the end flaps of the carton. In continued operation, of course, the operator would merely start one carton through the end folding plates and repeat his side sealing and folding operations to immediately place another carton between the end folding plates, each succeeding carton pushing the preceding carton ahead of it.

From the above description it should be apparent that the sealing machine eliminates a great many of the folding, holding and turning motions required to seal a bag and carton en-

tirely by hand. All of the operator's motions are performed directly in front of him and there is no necessity for turning the carton end for end or holding one fold while another fold is being sealed. The machine will therefore increase the output of each operator materially and at a relatively small investment of capital since the sealing machine is simple and inexpensive to manufacture and is adjustable for sealing various sizes of cartons.

It should be understood that the particular carton illustrated is an example only and that other cartons having different folds may be substituted therefor. The terms, end, side, top and bottom as applied to the parts of the carton are used for convenience in description only and cartons having other relative proportions may be used. I have described my invention in a highly practical commercial embodiment thereof and have not attempted to show other modifications as it is felt that persons skilled in the art can make such changes as are desired without further disclosure.

Having thus described my invention, what I claim as new and desire to secure by Letters Patent, is:

1. In combination with a sealing device for cartons and the like having a base with top panels and folding and sealing plates adjustably mounted on top thereof, a pair of brackets extending from the front of said base, a side sealing plate supported between said brackets and vertically along the front of said device, a plurality of teeth formed along the lower edge of said sealing plate, a jaw member having teeth cooperative with said teeth on said side sealing plate pivotally supported on said brackets, an electrical heating unit associated with said sealing plate and adapted to heat said plate and teeth for heat sealing a carton and crimping and sealing a liner bag, a work support comprising a generally vertical back plate with a forwardly turned flange along the lower edge thereof pivotally mounted on said brackets by means of ears turned backwardly from the ends of said back plate, said work support being tiltable from a lowered position in front of said side sealing plate to a raised position against said top panel to expose said side sealing plate and form an upper guide surface thereabove, and a foot pedal for operating said jaw member.

2. In combination with a sealing device for cartons and the like having a frame with top panels and folding and sealing plates adjustably mounted on top thereof, a pair of brackets extending from the front of said frame, a side sealing plate supported between said brackets and vertically along the front of said device, a jaw member cooperative with the lower edge of said

side sealing plate pivotally supported on said brackets, an electrical heating unit associated with said sealing plate and adapted to heat said plate for heat sealing a carton and sealing a liner bag, and a work support comprising a generally vertical back plate with a forwardly turned flange along the lower edge thereof pivotally mounted on said brackets by means of ears turned backwardly from the ends of said back plate, said work support being tiltable from a lowered position in front of said side sealing plate to a raised position to expose said side sealing plate.

3. A semi-automatic folding and sealing device for closing cartons comprising a frame, flap folding and sealing plates adjustably mounted on top of said frame, a flat panel on said frame in front of said plates, a manually operable sealing plate mounted on the front of said frame below the front of said panel, and an angle shaped work supporting member pivotally mounted on the front of said frame and swingable between a lower shielding position in front of said manually operable sealing plate and a raised position against said panel exposing said manually operable sealing plate and acting as a guide for a carton pressed against the under side of said supporting member.

4. A semi-automatic folding and sealing device for closing cartons comprising a frame, flap folding and sealing plates adjustably mounted on top of said frame, a manually operable sealing plate mounted on the front of said frame, and a work supporting member pivotally mounted on the front of said frame and swingable between a lower shielding position in front of said manually operable sealing plate and a raised position exposing said manually operable sealing plate and acting as a guide for a carton pressed thereagainst.
